(57) CLAIM

The ornamental design for a tee shirt, as shown and described.

DESCRIPTION

FIG. 1 is a perspective view of a tee shirt, showing a first embodiment of my new design;

FIG. 2 is a front elevational view of FIG. 1;

FIG. 3 is a rear elevational view of FIG. 1;

FIG. 4 is a right-side elevational view of FIG. 1, the left-side elevational view being a mirror image thereof;

FIG. 5 is a top plan view of FIG. 1;

FIG. 6 is a bottom plan view of FIG. 1;

FIG. 7 is a perspective view of a second embodiment thereof;

FIG. 8 is a front elevational view of FIG. 7;

FIG. 9 is a rear elevational view of FIG. 7;

FIG. 10 is a right-side elevational view of FIG. 7;

FIG. 11 is a top plan view of FIG. 7;

FIG. 12 is a bottom plan view of FIG. 7;

FIG. 13 is a perspective view of a third embodiment thereof;

FIG. 14 is a front elevational view of FIG. 13;

FIG. 15 is a rear elevational view of FIG. 13;

FIG. 16 is a right-side elevational view of FIG. 13;

FIG. 17 is a top plan view of FIG. 13;

FIG. 18 is a bottom plan view of FIG. 13;

FIG. 19 is a perspective view of a fourth embodiment thereof;

FIG. 20 is a front elevational view of FIG. 19;

FIG. 21 is a rear elevational view of FIG. 19;

FIG. 22 is a right-side elevational view of FIG. 19;

FIG. 23 is a top plan view of FIG. 19; and,

FIG. 24 is a bottom plan view of FIG. 19.

The broken lines showing a person in the perspective views of the drawings depict environmental matter and form no part of the claimed design. The remaining broken lines represent stitching, and are part of the claimed design.

1 Claim, 20 Drawing Sheets
